TRIMMER MECHANISM FOR SEWING MACHINES

Edward M. Hanf, Bridgeport, Conn., assignor to The Singer Manufacturing Company, Elizabeth, N. J., a corporation of New Jersey

Application May 11, 1935, Serial No. 20,956

4 Claims. (Cl. 112—127)

This invention relates to trimmer mechanisms for sewing machines and more particularly to improvements in underedge trimmer mechanisms designed for trimming off the margin of the under 5 of two or more plies of material in the operation of uniting said plies by stitches.

It is the primary object of the present invention to provide durable means for maintaining an effective shearing relationship between 10 the movable and ledger-blades of a trimmer mechanism and more specifically in the trimmer mechanism disclosed in the U. S. patent to J. C. Ringe, No. 1,526,436, Feb. 17, 1925.

The invention consists in the improved knife-bar guiding means hereinafter described and as set forth in the appended claims.

In the drawing, Fig. 1 is a front end elevation of the bracket-arm head and a portion of the cloth-plate of a sewing machine containing a preferred embodiment of the present invention. Fig. 2 represents a section of the bracket-arm head in a vertical plane adjacent to the trimmer-bar. Fig. 3 represents a perspective view of the trimmer-bar guide-stud. Figs. 4 and 5 represent 25 perspective views of the trimmer-bar guide-brackets.

The sewing machine, partly illustrated in the drawing and more fully described in said prior Patent No. 1,526,436, has a horizontally disposed 30 bed-plate 1 supporting a throat-plate 2, suitably apertured to receive a feed-wheel 3 and recessed in its upper face to receive a ledger-blade 4. Adjacent to the ledger-blade 4, the throat-plate is provided with a vertically inclined trimmer-knife aperture 5. Overhanging the bed-plate 1 is a bracket-arm head 6 in which is pivotally hung a swinging frame 7 providing 35 bearings for a vertically reciprocatory needle-bar 8 carrying at its lower end a needle 9. Journaled for vertical movement in suitable bearings provided in the bracket-arm head 6 is a presser-bar 10 carrying at its lower end a roller-presser 40 11 yieldingly opposed to the feed-wheel 3.

Vertically slidable in the upper end of the presser-bar 10 is a spring-pressed trimmer-lifter rod 12 engaging an angular plate 13 suitably secured upon the upper end of a trimmer-bar 14. The trimmer-bar 14 is journaled within the head 6 for endwise reciprocatory and laterally vibratory 45 movements resulting in a vertically inclined operative path of said bar. For this purpose, one side edge of the trimmer-bar, adjacent to its upper end, is provided with a rounded protuberance 15 slidably engaging a wall 16 of a trimmer-bar guiding recess 17 in the bracket-arm head 55

6. Opposed to the recess-wall 16 is a convexly curved wall 18 engaged by the slightly concave edge 19 of the trimmer-bar opposite to the protuberance 15, thereby providing a sliding fulcrum for the trimmer-bar which is confined by 5 the walls of the recess 17 to movements in a vertical plane transverse to a vertical plane containing the line of feed of the work.

Adjacent to its lower end, the trimmer-bar 14 is provided with substantially parallel guides 20, 10 21 constituted by the edges of said bar which are opposed to each other transversely of the line of seam formation, said guides being inclined to the length of the trimmer-bar. The guide 20 slidably engages a guideway 22 comprising the 15 diametral face of a substantially semi-circular guide-stud head 23 having a bearing trunnion 24. The arcuate portion of the segmental head 23 of the guide-stud and the trunnion 24 thereof are journaled in a shouldered bearing-aperture 20 25 provided in one member 26 of an angular supporting-bracket, the other member 27 of said bracket being secured by screws 28 upon the head 6 of the machine bracket-arm. The bracket-member 26 is partly cut away to provide a trimmer-bar confining face 29 terminating in a vertically inclined shoulder 30 intersecting the guide-stud bearing aperture 25. The guideway 22 of the guide-stud projects beyond the bracket-shoulder 30, thereby constituting a rock- 30 ing bearing for the trimmer-bar guide 20 independently of said shoulder.

Directly opposite to the guideway 22 of the guide-stud is an adjustable screw 31 endwise engaging the trimmer-bar guide 21, said screw 35 31 being adjustably threaded into a bracket 32 secured by screws 33 upon the head 6 of the machine bracket-arm. It will be understood that by reason of the described guiding means for the trimmer-bar 14, the lower end of the 40 trimmer-bar will be vibrated laterally upon endwise reciprocation of said trimmer-bar. The pivotal guide-stud 23, 24 provides for maintaining the entire length of the guideway 22 of said 45 guide-stud in engagement with the guide 20 of the endwise reciprocatory and laterally vibratory trimmer-bar 14, thereby insuring accurate guiding of said trimmer-bar.

Adjustably secured by screws 34 to the lower 50 end of the trimmer-bar 14 is a knife-holder 35 to which the vertically inclined trimmer-knife 36 is suitably secured.

The trimmer-knife has the usual guide-finger 37 adapted to enter the throat-plate aperture 5, 55

and has a cutting edge 38 which coacts with the ledger-blade 4 to sever the work.

- Endwise reciprocatory movements are imparted to the trimmer-bar 14 by a vibratory arm 39, 5 releasably connected to said bar by a stud 40 adapted to enter a notch 41 in a side edge of the trimmer-bar, said arm 39 being carried by a rock-shaft 42 which may be actuated in any usual or suitable manner.
- 10 Having thus set forth the nature of the invention, what I claim herein is:—
1. Trimmer mechanism for sewing machines comprising, a trimmer-knife carrying bar provided with a guide inclined to the length of said bar, actuating mechanism for endwise reciprocating said bar, a rocking guideway slidably engaged by said guide, and means effective to maintain said guide and guideway in sliding engagement.
- 15 2. Trimmer mechanism for sewing machines comprising, a trimmer-knife carrying bar provided with a guide, actuating mechanism for endwise reciprocating said bar, a rocking guide-stud slidably engaged by said guide, and means 20 adjustably opposed to said guide-stud for main-

taining said guide and guide-stud in sliding engagement.

3. Trimmer mechanism for sewing machines comprising, a trimmer-knife carrying bar provided with a guide inclined to the length of said bar, actuating mechanism for endwise reciprocating said bar, a rocking guide-stud having a trunnion and a head providing a guideway slidably engaged by said trimmer-bar guide, a journal-bearing for the trunnion of said guide-stud, 10 and means effective to maintain said guide and guideway in sliding engagement.

4. Trimmer mechanism for sewing machines comprising, a trimmer-knife carrying bar provided with substantially parallel guides, actuating 15 mechanism for reciprocating said bar, a rocking guide-stud having a trunnion and a segmental head providing a guideway slidably engaged by one of said trimmer-bar guides, a journal-bearing for the head and trunnion of said guide-stud, 20 and an adjustable screw disposed directly opposite to said guideway and endwise engaging the other of the trimmer-bar guides.

EDWARD M. HANF. 25
